SYLVESTER ARMITAGE, OF HIGHLAND PARK, MICHIGAN, ASSIGNOR TO GENERAL MOTORS CORPORATION, OF DETROIT, MICHIGAN, A CORPORATION OF DELAWARE

BUTTERFLY-VALVE EXHAUST PIPE

Application filed December 18, 1927. Serial No. 241,098.

This invention relates to internal combustion engines as used on automotive vehicles and has particular reference to a means for diverting the flow of exhaust gases to cause a preheating of the fuel mixture.

During the starting period and in cold weather, internal combustion engines do not function any too well, and it is accordingly one of the principal objects of the invention to equip the engine with a suitable heating arrangement whereby a larger amount of the hot exhaust gases may be caused to flow around the fuel intake in order that the incoming fuel mixture may be more readily heated and thus increase its firing condition.

The invention is principally concerned with internal combustion engines of the V-type having two banks of cylinders arranged in V-form. Each bank has an exhaust manifold which are connected at their centers by a transverse passage which will permit the flow of the exhaust gases from one manifold to another. Within this transverse passage there is arranged the fuel intake leading to the intake manifold.

In one or both of the exhaust manifolds I arrange a valve, preferably of the butterfly type, which is capable of hand operation by the driver at the dash. This valve is normally open to allow the free passage of the exhaust gases, but during the starting period or in cold weather it may be closed to any desired degree to thereby force the exhaust gas to pass from the manifold containing the valve to the other manifold, through the intermediary of the central transverse passage. This closing of the valve will accordingly cause a much greater amount of hot gas to flow through the transverse passage which will cause an increased amount of heating of the incoming carbureted fuel mixture flowing through the intake passage.

In internal combustion engines of the V-type two preferred methods of removing the exhaust are in use. The first method uses individual exhaust pipes for each bank, while the second method joins the exhaust manifolds at one end and allows the exhaust gas to pass off through a common exhaust pipe.

In the second instance the butterfly valve may

be placed in an exhaust manifold at its point of emergence with the connecting member of the two manifolds.

If desired, the throttle valve of the usual carburetor may be interconnected with the lever which operates the butterfly valve in the exhaust. This connection will permit of the simultaneous operation of the throttle valve and exhaust valve by the use of a single lever. In practice, I prefer to use the accelerator pedal as the common means for operating the throttle and valve.

The exhaust manifold will preferably be so shaped that a lip or fin extends over the exhaust opening of each cylinder to prevent the exhaust gas from the adjoining cylinder tending to turn thereinto. As the exhaust gas passes the lip, its momentum will have a tendency to pull the exhaust gas from the exhaust port and thereby increase the efficiency of the engine.

Where the exhaust manifolds are joined at their ends by a common connection, an additional lip is preferably positioned within the connection at the point where the exhaust gases from the two manifolds meet. The exhaust gas from the one cylinder bank will thereby surge past the lip and tend to draw the exhaust gases from the other cylinder, the action being in the nature of a siphon effect.

The invention is disclosed on the accompanying drawing in which:

Figure 1 is a plan view of the V-type internal combustion engine having a single exhaust pipe and showing my invention applied thereto.

Figure 2 is a horizontal sectional plan view through the manifolds of Figure 1.

Figure 3 is a plan view similar to Figure 1, showing the invention applied to a V-type engine having individual exhaust pipes for each bank of cylinders.

Figure 4 is a detailed view of the accelerator pedal and connections shown in Figure 3.

Figure 5 is a sectional view on the line 5—5 of Figure 4.

Figure 6 is a sectional view on the line 6—6 of Figure 4.

Referring to the numbered parts on the drawings, 10 shows so much of an automo-

tive vehicle as is necessary to illustrate the invention. 12 is an internal combustion engine of the V-type having the two banks 14 and 16, each bank having an exhaust manifold as shown at 18 and 20. These two exhaust manifolds 18 and 20 are united at their front end by means of a connection 22 which delivers the exhaust gases into a common exhaust pipe 24. The manifold 20 terminates 10 at 26 and has applied thereto a short section 28 in which there is mounted a valve 30 which may be of any suitable kind, but is preferably of the butterfly type. This valve is pivotally mounted within the section 28 by means of 15 a stem 32 having secured thereto at one end an arm 34 connected by means of a link 36 to an operating lever 38 located at the dash 40 of the vehicle 10. Instead of using the section 28, the butterfly valve may be positioned 20 in an arm of the connection 28 or be mounted in the manifold proper, which will then extend to the connection 22 and include the length taken up by the section 28.

The two manifolds 18 and 20 are united 25 by means of a transverse passage 42, preferably positioned between the centers of the two manifolds. This passage 42 surrounds the intake 44 leading from the carburetor 46 and conducting the gases into the intake 30 manifolds 48. The gases as they pass through the transverse passages 42 and around the intake 44 serve to heat the incoming carbureted mixture prior to its entry into the firing chambers. Normally, or when 35 the valve 30 is open, only a relatively small amount of exhaust gas pulsates through the passage 42, but with the valve in closed position, all of the exhaust gas from one bank is forced through the passage, causing a relatively very much greater preheating of the 40 fuel mixture.

During the starting period or in cold weather when it is desired to have additional heat transmitted to the carbureted fuel, the lever 45 38 may be operated to swing the valve 30 to thereby more or less close the exhaust opening at the section 28. This will cause the exhaust gases from the manifold 20 to pass through the passage 42 and into the exhaust 50 manifold 18 from where they will be delivered to the connection 22 and into the exhaust pipe 24. As the valve 30 is subject to manual control, the heat necessary for the incoming mixture may be controlled at the will of the 55 driver. If desired, the valve 30 may be interconnected with the throttle valve so that both may be simultaneously operated.

Referring to Figure 2, each exhaust port 50 is provided with an overhanging lip or 60 fin 52, the purpose of which is to prevent the tendency of the exhaust gas from one cylinder to enter the exhaust passage of the next adjoining cylinder. The fin 52 has the function of causing the gas from one cylinder to 65 pass the exhaust port of the adjoining ex-

haust with a surge and its momentum will tend to pull the exhaust gases out of the exhaust port of the latter, thereby increasing the efficiency of the engine.

The connection 22 it will be noted has a fin 54 positioned at the point of junction in the connection of the arm 23 leading to the manifold 20. The function of the fin or lip 54 is similar to the function of the lips 52; that is, as the exhaust gas from the manifold 18 surges past the lip 54, its momentum will tend to draw the exhaust gas from the manifold 20, thereby increasing the efficiency of the engine.

The structure of Figure 3 differs from that of Figure 1 in that the V-type engine has separate exhaust pipes 56 and 58 leading from the exhaust manifolds 18' and 20'. The transverse passage 42 and the carburetor 46 together with the intake 44 are in all respects similar to the corresponding parts shown on Figures 1 and 2.

The butterfly valve 30' in the species of Figure 3 is preferably journaled in a section 60 which forms a part of the manifold 20'. This section 60 forms a connection between the manifold 20' and the exhaust pipe 58 and these parts are secured together by means of the flanges 62 and bolts 64. While I have shown the valve as positioned in a separate section, this section may be omitted and the valve placed either in the manifold proper or in the exhaust pipe.

The valve 30' has the stem 66 and secured to the stem is the lever or arm 68 which in turn is secured to a rod 70 fastened at 72 to an arm 74 which is secured to the accelerator pedal 76 pivoted at 78 to a bracket 79 secured to the foot board 80.

The attachment of the link 70 to the arm 68 is made by means of two springs 88 positioned at either side of the arm 68 and held in place by means of the nuts 90 fastened to the rod 70. This forms a resilient connection and permits of a more easy operation of the butterfly valve 30'.

The carburetor 46 has the usual throttle valve, the operating arm of which is shown at 82 and secured to this arm is the link or rod 84 connected at one end as shown at 86 to the end of the arm 74.

Due to the fact that the links 70 and 84, which are connected respectfully to the butterfly valve and to the throttle valve, are pivotally connected to the accelerator pedal 76 it will be seen that the valve 30' and the throttle valve are capable of simultaneous operation. It is preferred that the arrangement be such that when the accelerator pedal is in closed throttle position the butterfly valve will close the exhaust manifold 20', thereby causing all the exhaust gases from this side of the engine to flow into the transverse passage 42, around the heating jacket of the intake manifold, into the second mani- 125 130

fold and thence out at the exhaust pipe. As the throttle is opened the butterfly valve 30' also opens so that at high speeds the butterfly valve will offer substantially no resistance to the exhaust gases.

5. If desired, a butterfly valve may be placed in both exhaust pipes and obviously but one of them operated at a time.

I claim:

10. 1. In combination with an internal combustion engine, a plurality of exhaust manifolds, means interconnecting with said manifolds, and means in one manifold to divert the exhaust gases into a second manifold.

15. 2. In combination with an internal combustion engine having a plurality of banks of cylinders, an exhaust manifold for each bank, means interconnecting with said manifold, a valve in one manifold for diverting the exhaust gas through a second manifold.

20. 3. In combination with an internal combustion engine having a plurality of exhaust manifolds, a passage interconnecting said manifolds, and a valve in one of said manifolds for diverting the exhaust gas through the passage and into a second manifold.

25. 4. In combination with an internal combustion engine having a plurality of manifolds, a passage connecting said manifolds at their centers, and a valve in one of said manifolds for diverting the exhaust gas through the passage and into a second manifold.

30. 5. In combination with an internal combustion engine having a plurality of interconnected exhaust manifolds, and a butterfly valve in one of said manifolds for forcing the gas therefrom through the connection and into a second manifold.

35. 6. In combination with an automotive vehicle, an engine having a plurality of exhaust manifolds, a passage interconnecting said manifolds, means in one manifold to divert the gases to a second manifold, and means operable from the inside of the vehicle for controlling the position of the first named means.

40. 7. In combination with an internal combustion engine having a plurality of exhaust manifolds, a plurality of connections between said manifolds, and means in one of said manifolds to divert the gases through one of said connections and into a second manifold and thence into a second connection.

45. 8. In combination with an internal combustion engine, a plurality of exhaust manifolds, means interconnecting said manifolds, and a valve in one manifold to divert the exhaust gases into a second manifold.

50. 9. In combination with an internal combustion engine, a plurality of exhaust manifolds, means interconnecting said manifolds, and a valve in one manifold operated from a remote point to divert the exhaust gases into a second manifold.

55. 10. In combination with an automotive ve-

hicle, an engine having a plurality of exhaust manifolds, a passage interconnecting said manifolds, a butterfly valve in one manifold to divert the gases to a second manifold, and means operable from the inside of the vehicle for controlling the position of the first named means.

60. 11. In combination with a V-type engine having two banks of cylinders, an exhaust manifold at each bank of cylinders, a connection between the two manifolds, a valve in one manifold adapted to close said manifold and divert the exhaust gas to the other manifold, and means interconnecting said manifolds at their ends to a common exhaust pipe.

65. 12. In combination with a V-type engine having two banks of cylinders, an exhaust manifold at each bank of cylinders, a connection between the two manifolds, a valve in one manifold adapted to close said manifold and divert the exhaust gas to the other manifold, means for delivering carburetted fuel to the engine, means in said connection to preheat said carburetted fuel, and means interconnecting said manifolds at their ends to a common exhaust pipe.

70. 13. In combination with an engine having a plurality of exhaust manifolds, means interconnecting said manifolds intermediate their ends, means interconnecting said manifolds at their ends, a section interposed between one manifold and the end connection, and means in said connection adapted to divert all the exhaust gas through said intermediate connection to one manifold.

75. 14. In combination with an engine having a plurality of exhaust manifolds, means interconnecting said manifolds intermediate their ends, means interconnecting said manifolds at their ends, a section interposed between one manifold and the end connection, and a valve in said connection adapted to divert all the exhaust gas through said intermediate connection to one manifold.

80. In testimony whereof I affix my signature. 110
